DESIGN FOR A PLAYHOUSE

August A. Olson, Bremerton, Wash.

Application May 12, 1944, Serial No. 113,560

Term of patent 14 years

(Cl. D34—15)

To all whom it may concern:

Be it known that I, August A. Olson, a citizen of the United States of America, residing at Bremerton, county of Kitsap, and State of Washington, have invented a new, original, and ornamental Design for a Playhouse, of which the following is a specification, reference being had to the accompanying drawing, forming a part there-of wherein:

Figure 1 is a front end view of a playhouse, showing my new design.

Figure 2 is a rear end view.

Figure 3 is a side view.

I claim:

The ornamental design for a playhouse, as shown.

AUGUST A. OLSON.
